(57) **CLAIM**

The ornamental design for brush attachment for hand held hair dryers, substantially as shown and described.

DESCRIPTION

FIG. 1 is a view in perspective of the brush attachment for hand held hair dryers shown mounted for use on a hair dryer;

FIG. 2 is a front elevation view of the brush attachment for hand held hair dryers of the present invention, the rear view being a mirror image thereof;

FIG. 3 is a right side elevation view of the brush attachment for hand held hair dryers of the present invention, the left side being a mirror image thereof;

FIG. 4 is a top plan view of the brush attachment for hand held hair dryers of the present invention; and,

FIG. 5 is a bottom view from beneath the brush attachment for hand held hair dryers of the present invention.

The broken line showing of the hair dryer in FIG. 1 is for illustrative purposes only and forms no part of the claimed design.
